US0D1040835S

(12) **United States Design Patent** (10) Patent No.: **US D1,040,835 S**
(45) Date of Patent: ** Sep. 3, 2024

(54) **DISPLAY SCREEN OR PORTION THEREOF WITH GRAPHICAL USER INTERFACE**

(71) Applicant: **Shenzhen Intellirocks Tech Co., Ltd.**, Shenzhen (CN)

(72) Inventors: **Ruixin Lin**, Guangdong (CN); **Chang Chen**, Guangdong (CN); **Wenlong Wu**, Guangdong (CN)

(73) Assignee: **SHENZHEN INTELLIROCKS TECH CO., LTD.**, Shenzhen (CN)

(**) Term: **15 Years**

(21) Appl. No.: **29/810,932**

(22) Filed: **Oct. 9, 2021**

(30) **Foreign Application Priority Data**

Aug. 5, 2021 (CN) 202130505653.6

(51) **LOC (14) Cl.** **14-04**

(52) **U.S. Cl.**

USPC **D14/485**; D14/489

(57) **CLAIM**

The ornamental design for a display screen or portion thereof with graphical user interface, as shown and described.

DESCRIPTION

FIG. 1 is a front view of a display screen or portion thereof with graphical user interface in accordance with a first embodiment of our new design; and,

FIG. 2 is a front view of a display screen or portion thereof with graphical user interface in accordance with a second embodiment of our new design.

The outermost broken lines in the figures show a display screen or portion thereof, and form no part of the claimed design.

1 Claim, 2 Drawing Sheets
